UNITED STATES PATENT OFFICE.

MURRAY C. BEEBE AND EDMUND M. WISE, OF FORT THOMAS, KENTUCKY, ASSIGNEES
TO THE WADSWORTH WATCH CASE COMPANY, OF DAYTON, KENTUCKY, A COR-
PORATION.

SERIAL-NUMBERING DEVICE.

Application filed July 30, 1921. Serial No. 488,730.

To all whom it may concern:

Be it known that we, MURRAY C. BEEBE and EDMUND M. WISE, citizens of the United States, residing at Fort Thomas, in the county of Campbell and State of Kentucky, have invented certain new and useful Improvements in Serial-Numbering Devices, of which the following is a specification.

Our invention relates to improvements in serial numbering devices and it more especially consists of the features hereinafter pointed out in the annexed claims.

The purpose of our invention is to provide means for optically projecting any desired symbols, numbers, etc., onto the sensitized surfaces of watch cases, etc., without using what is known as contact printing through a negative; and that provides a serial number film which has alternate clear and numbered areas, and in addition has means for self-centering the numbers as they come into proper position.

With these and other ends in view, we illustrate in the accompanying diagrammatic drawing such instances of adaptation as will disclose the broad underlying features without limiting ourselves to the specific details shown thereon and described herein.

Figure 1 is a diagrammatic view in which a serial number film is combined with a pattern transparency.

Fig. 2 is a diagrammatic elevation of a patterned watch case and a serial number film.

In practically carrying out our system we are not limited to any special objects on which serial numbers are to be applied, or whether such numbers shall be combined with a peculiar repetitive design, but claim the broad features of automatically or otherwise applying serial numbers on any desired surface, either in consecutive or any arbitrary grouping order.

The use of our device simply requires the production of a transparency 1 of the design, with which is to be combined an identifying symbol or number. The design or number may be either a negative or a positive according to the effect that is desired. In substance, such a transparency, if a positive, is not unlike well known lantern slides. The optical part of our system comprises a source of light, usually an electric arc lamp 3, a condenser 4, the transparency

1, the projection lens 2; and the sensitive 55 plane-surface 5, or a curved surface.

Whenever manufacturers of watch cases desire to place serial numbers on successive cases, we find it very efficient to use a film 6 having consecutive serial numbers 7 placed 60 thereon with blank areas between. Such a film is combined with any desired pattern 9 that has an unoccupied space for the serial number and any other insignia or symbol. The film 7 is moved along side the image 65 plate 1, as shown in Fig. 1, between the spools 10 as these are turned by means of the handles 11. In order to cause the numbers on the film to register with the open space of the image in the direction of the 70 traverse of the film, we may form V shaped notches 8 on one edge of the film opposite the center point of each number and cause the film to pass between guides 13 on each side of the image slide 1 to hold it against 75 lateral shifting. A "centering" wheel 12, of some thickness, on an arm 14 fulcrumed at 15 will ride along the edge of the film and move into the notches 8 under the tension of a spring 16.

In this way the accurate registration of the numbers is easily brought about, as the wheel 12 when it passes into a notch 8 will instantly indicate to the operator that the movement of the film must be stopped and 85 on account of the tension of the spring 16 and the V sides of the notches 8, the wheel will automatically center the numbers, either advancing or retarding the film slightly as may be required.

The development of the image may be performed in any well known manner that conforms to the sensitizing medium which is used, for instance if the surface coating is bichromated gelatine the developing agent 95 is water of the required temperature; if otherwise, a corresponding change is made in the developer.

What we claim is:

1. The method of producing serial numbers on watch cases and the like, which consists in separately covering watch cases with a light-sensitive coating, in separately subjecting the coated cases to an ornamental image by projection, in simultaneously projecting serial numbers onto the same surface, and in changing the number images coordinately with the change of watch cases.

2. In serial numbering systems, an ornamental image having a clear area thereon, a movable film having serial numbers or other symbols in numerical sequence, means 5 for successively registering such symbols in register with the clear space of the ornamental image, and means for projecting the ornamental image and the recurring serial numbers simultaneously onto a suitable 10 light-sensitive surface.

3. In serial numbering devices, a moving film having serial numbers thereon spaced apart with a transparent area between adja-

cent numbers, an ornamental image having a clear space corresponding approximately 15 to the area allotted to the numbers on the film, means for periodically moving the film to bring a new number adjacent the clear space of the image, and means for projecting light rays through the film and ornamental 20 image simultaneously so as to impress the same upon a suitable light-sensitive surface.

In testimony whereof we affix our signatures.

MURRAY C. BEEBE.
EDMUND M. WISE.
